P. H. LEIPOLD

PIPE CUTTING IMPLEMENT

Filed Jan. 17, 1924

INVENTOR,
Paul H. Leipold,

BY

Geo. Kimmel
ATTORNEY.

UNITED STATES PATENT OFFICE.

PAUL H. LEIPOLD, OF FORT WAYNE, INDIANA.

PIPE-CUTTING IMPLEMENT.

Application filed January 17, 1924. Serial No. 686,864.

To all whom it may concern:

Be it known that I, PAUL H. LEIPOLD, a citizen of the United States, residing at Fort Wayne, in the county of Allen and State of Indiana, have invented certain new and useful Improvements in a Pipe-Cutting Implement, of which the following is a specification.

This invention relates to pipe cutting implements, and has for one of its objects to improve the construction and increase the efficiency and utility of the device.

Another object of the invention is to provide a device of this character wherein the cutting elements are renewable without discarding the remaining parts of the implement.

Another object of the invention is to provide a device of this character having means for adjusting the pipe engaging jaws to operate on pipes of varying sizes.

With these and other objects in view the invention consists in certain novel features of construction as hereinafter shown and described and then specifically pointed out in the claims, and in the drawings illustrative of the preferred embodiment of the invention—

Figure 1 is a side elevation, and

Fig. 2 is an edge view, of the improved implement;

Fig. 3 is a section, enlarged, on the line 3—3 of Fig. 1;

Fig. 4 is a section, enlarged, on the line 4—4 of Fig. 1;

Fig. 5 is a detached view of one of the cutting blades;

Fig. 6 is a sectional detail of the adjustable joint of the improved implement; and

Fig. 7 is a plan view of a part of one of the body members.

The improved implement is designed more particularly for severing lead piping and like relatively soft materials, and comprises coacting body portions 10—11 pivotally united.

One of the body members, for instance the member 10, is formed with a transverse slot with enlarged ends 25 and 26 and a contracted central portion 27, as shown more clearly in Figure 7, while the member 11 is formed with an aperture to receive a clamp bolt 13, the body of the bolt engaging the aperture in the member 11 and formed with an enlargement 28 to engage alternately in

the enlargements of the slot. A clamp nut 14 is applied to the bolt, as shown, the object to be hereinafter explained.

The confronting faces of the body portions 10 and 11 are preferably reversely curved as shown, and bearing respectively upon the body portions are cutting blades 17 and 18 with their confronting edges reversely curved and knife edged. Intermediate the ends of blade 17 is a knife edged cavity 19, while a similar knife edged cavity 20 is formed in the blade 18.

The confronting faces of the body members in advance of the pivot 13, are recessed to receive the cutting blades 17 and 18, the inner end of the recesses forming stop shoulders against which the inner ends of the blades bear and are thereby effectually supported from displacement longitudinally of the body members.

Bearing upon the blade 17 is a holding plate 21, while a similar holding plate 22 bears upon the blade 18.

As shown by dotted lines in Fig. 1, the inner ends of the holding members 21 and 22 overlap the adjacent parts of the body members, and thus protect them, and supplement the holding force of the stop shoulders.

The three parts 10—17 and 21 are coupled by clamp screws 23, while the three parts 11, 18 and 22 are coupled by like clamp screws 24. By this means the cutting blades are firmly supported in position for use, but may be readily detached for renewal.

In operating with the improved implement, the cutting blades 17 and 18 are disposed upon opposite sides of the pipe to be severed, and pressure applied to the hand grips 15 and 16 and rotary or oscillatory motion imparted to the implement to cause the knife edges of the blades to cut into the pipe, the recesses 19 and 20 serving as teeth to increase the efficiency of the cutting action.

The blades operating equally from opposite sides of the pipe sever the pipe uniformly and without reducing the size of the pipe or distorting it in any manner, leaving a square uniform end to the pipe.

By the arrangement shown when the bolt 13 is disposed with its enlargement 28 in the enlarged end 25 of the slot the members 10 and 11 will be in position to cause the cutters 17—18 to clasp a relatively small pipe,

and when the enlargement 28 of the bolt is disposed in the enlarged end 26 of the slot, the members 10 and 11 will be in position to cause the cutters 17 and 18 to clasp a larger pipe, as will be obvious.

The implement is simple in construction, can be inexpensively manufactured, of any suitable size or material.

10 The blades 17 and 18 may be varied in form as required, and a plurality of sizes and forms of blades may be employed with each of the coacting body portions.

15 The preferred embodiment of the invention is disclosed in the drawings and set forth in the specification, but it will be understood that modifications within the scope of the claimed invention may be made in the construction without departing from the principle of the invention or sacrificing any 20 of its advantages.

Having thus described the invention, what is claimed as new is:—

An implement of the class described, comprising coacting body members pivotally united with the confronting faces recessed in advance of the pivot with stop shoulders forming the inner ends of the recesses, a cutting blade in each of the recesses and overhanging the confronting edges of the body members and each bearing against one of the stop shoulders, a holding plate bearing over each of the blades with one end overhanging the adjacent stop shoulder, and fastening devices operating through the recessed portions of the body members, the cutting blades, and the holding plates. 25 30 35

In testimony whereof, I affix my signature hereto.

PAUL H. LEIPOLD.
